DESIGN FOR A WALL CLOCK

Nicholas J. Faniola, Plainville, Conn.

Application September 24, 1947, Serial No. 141,561

Term of patent 14 years

(Cl. D42—7)

To all whom it may concern:

Be it known that I, Nicholas J. Faniola, a citizen of the United States, residing in Plainville, county of Hartford, and State of Connecticut, have invented a new, original, and ornamental Design for a Wall Clock, of which the following is a specification, reference being had to the accompanying drawing, forming a part thereof.

Fig. 1 is a front view of the wall clock, showing my new design.

Fig. 2 is a side view of the same.

My design for a wall clock is characterized by the concavo-convex intermediate ribbed section adjacent the base, as illustrated on the drawing.

I claim:

The ornamental design for a wall clock, as shown and described.

NICHOLAS J. FANIOLA.
